UNITED STATES PATENT OFFICE

2,468,694

SOLID FUEL BURNING WATER HEATER

Thomas W. Torr, Dowagiac, Mich., assignor to
The Rudy Furnace Company, Dowagiac, Mich.

Application February 28, 1944, Serial No. 524,154

3 Claims. (Cl. 126—344)

1

The main objects of this invention are:

First, to provide a water heater which is of large capacity and is efficient in utilization of fuel.

Second, to provide a water heater which may be formed mainly of steel, the inner wall member providing a combustion chamber as well as the inner wall of the water reservoir whereby an effective transmission of heat results and excessive heating or overheating is prevented.

Third, to provide a structure in which the joints are mainly welded joints with the parts so arranged that the heating contraction and expansion stresses are such as to place no undue strain on the joints.

Fourth, to provide a water heater in which free movement of the water is provided, minimizing the tendency to collect lime and the like.

Fifth, to provide a structure having these advantages which is economical in material, light in weight and at the same time strong and durable.

Further objects pertaining to details and economies of the invention will definitely appear from the description to follow. The invention is defined in the claims.

A structure which embodies the features of the invention is clearly illustrated in the accompanying drawing, in which:

Fig. 1 is a fragmentary front view of a water heater embodying the invention, partially in vertical section on line 1—1 of Fig. 2.

Fig. 2 is a fragmentary side elevation with parts broken away further illustrating the structural details.

Fig. 3 is a view partially in section on a line corresponding to line 3—3 of Fig. 1.

Fig. 4 is a side perspective view of the closure for the grate opening facilitating the positioning and removal of the grate.

Fig. 5 is a detail section on line 5—5 of Fig. 2.

The embodiment of the invention illustrated comprises the outer wall member 1 and the inner wall member 2 disposed concentrically. These wall members are formed of steel, either sheet steel rolled into tubular form or from seamless steel tubes. The outer wall member projects substantially below the inner wall member for purposes which will appear. These wall members are fixedly secured together by means of the top and bottom annular members 3 and 4 disposed be-

2

tween them and provided with flanges 5 at each edge. These flanges are welded throughout to the wall members. This provides an annular reservoir 6 extending from top to bottom and the inner wall member constitutes a combustion chamber 7.

The combustion chamber 7 is provided with a top member 8, the edges 9 of which are welded to the inner wall member. This top member is provided with a fuel door opening 10 and a fire door or closure 11 therefor, the opening being surrounded by a downwardly offset flange 12 constituting a seat for the door 11. The top member is also provided with a flanged flue opening 13 receiving the flue 14.

The water supply pipe 15 is connected to the bottom of the water reservoir at one side, while the discharge 16 is connected to the opposite side at the top of the reservoir. This insures a free circulation of the water around the combustion chamber. The water reservoir is of uniform width throughout.

The portion 17 of the outer wall member which projects below the inner wall member has a front portion of section thereof cut away to receive the ashpit front wall member 18. The rear edges of this front wall member are welded to the edges of the outer wall member at 19 while the top portions 20 of this ashpit front wall member are shaped to fit the outer wall member at 21 and are welded thereto. The ashpit door 22 is pivoted at 23 on this member 18 and is provided with a draft damper 24.

The grate, made up of two sections 25, is supported at the rear by means of the bar 26 in supporting relation to the lower annular member 4 as shown in Fig. 2, and welded at 27 to the inner side of the outer wall, the grate sections being provided with rear journals 28. The front ends of the grate sections are supported by journals 29 and 30 which engage the bar 31 carried by the closure 32 for the opening 33 provided to facilitate the introduction and removal of the grate sections. This closure 32 is detachably secured by means of the bolts 34. The journal 30 is extended to receive a shaker handle. An ashpan is indicated at 35. No bottom is illustrated in the drawing, and when mounted on a cement foundation no bottom is needed. An ashpit bottom may be provided if desired.

While the combustion chamber wall is thin and permits effective radiation or transfer of heat to the water in the reservoir, it is protected by this effective radiation from becoming overheated. The welded joints for the reservoir are not subjected to severe stresses due to expansion and contraction but as a matter of fact there is some pressure exerted from the inside shell or wall outwardly and from the outside shell inwardly on the top and bottom rings. This is due to the fact that the inner shell 2 expands outwardly more than the outer shell 1, because the inner shell gets hotter than the outer shell.

The structure is highly efficient in heating capacity and is light in weight, a relatively small amount of material being required. The inlet and outlet openings being on opposite sides results in a cross flow in water movement which eliminates substantially all bubbling or gurgling noises. The capacity of the heater may be increased by increasing the diameter of the outer shell or wall relative to the inner wall or shell, and this results in slowing up the flow of water in the annular space between the inner and outer shells. The heater is particularly desirable for use in connection with a storage tank which, however, is not illustrated.

The feed door at the top of the heater may be used to check the draft, that is, by leaving it slightly open. This does not result in the escape of the products of combustion through the opening as the opening being relatively slight, outside air is drawn therethrough directly into the flue. If desired the top can be of the dome water jacket type, but it is not deemed necessary to illustrate such a structure.

The heater is very economical to produce, both in the matter of materials and labor. At the same time it is highly efficient.

Having thus described my invention what I claim as new and desire to secure by Letters Patent is:

1. In a water heater, the combination of outer and inner concentrically disposed tubular steel wall members, the outer wall member having a bottom portion extending below the bottom of the inner wall member to provide an ashpit wall, a segmental front portion of said outer wall member being cut away, an annular reservoir including said outer and inner tubular wall members and including an annular member connected to the lower end of the inner tubular wall member and welded to the outer tubular wall member, the inner wall member constituting a combustion chamber wall, an ashpit front wall member spaced a substantial distance below said annular member and projecting outwardly beyond the outer tubular wall member and having its rear and top edges welded to the edges of the remaining ashpit wall portion of said outer wall member, a grate disposed in a plane below said annular member and above the top of said outwardly projecting ashpit front wall member, a grate supporting bar for the rear end of said grate disposed in supporting relation to said annular member of said water reservoir, and welded at its ends to the inner side of said outer wall member, said outer wall member having an opening in the front of the ashpit portion thereof and disposed below said annular member and above the outwardly projecting portion of said ashpit front wall mem-

ber through which the grate may be introduced or removed, and a detachable closure for said opening provided with a supporting bar for the front end of the grate.

2. In a water heater, the combination of outer and inner concentrically disposed tubular steel wall members, the outer wall member having a segmental ashpit wall portion extending below the bottom of the inner wall member, an annular reservoir including said outer and inner tubular wall members and including an annular member connected to the lower end of the inner tubular wall member and welded to the outer tubular wall member, the inner wall member constituting a combustion chamber wall, an ashpit front wall member spaced a substantial distance below said annular member and projecting outwardly beyond the outer tubular wall member and having its rear and top edges welded to the edges of the ashpit wall portion of said outer wall member, a door to said ashpit front wall member, a grate disposed in a plane below said annular member and above the outwardly projecting ashpit front wall member, and supports for said grate mounted within said outer wall member, said outer wall member being provided with an opening disposed between said annular member and said ashpit wall front portion through which said grate may be introduced or removed.

3. In a water heater, the combination of laterally spaced outer and inner concentrically disposed tubular steel wall members, the outer wall member having a base portion extending below the bottom of the inner wall member, annular top and bottom members connected to said inner wall member and to said outer wall member for holding the same in spaced relation to provide an annular water reservoir, the inner wall member constituting a combustion chamber wall, a grate disposed in the outer tubular wall member and disposed below the level of the lower end of the inner tubular wall member, said outer tubular wall member having an opening therein below the level of the lower end of the inner tubular wall member through which the grate may be introduced or removed, a detachable closure for said opening, means for supporting said grate, said means including said detachable closure.
